DESK CALENDAR

John F. Bannon, Providence, R. I., assignor to
Defiance Sales Corporation, New York, N. Y., a
corporation of New York

Application April 30, 1943, Serial No. 485,254

3 Claims. (Cl. 40—120)

My invention relates to desk calendars and more particularly to a desk calendar stand, in which a calendar pad made up of successive sheets or leaves for successive days of the year as, for example, one for each day, is mounted on a base so that the sheets or leaves of the pad may be successively turned from one half of the base to the other to expose the successive leaves.

Pads of the above type have holding means as, for example, a pair of wire arches extending upwardly from the base and threaded through correspondingly spaced holes in the leaves of the pad.

When one pad is to be replaced by another to begin a new year, the wire arches must be tilted toward a horizontal position. To enable the wire arches to be thus tilted and at the same time to avoid a hinge above the surface of the pad, relatively long slots must be formed to receive one arm of the arches and this has the disadvantage of breaking up the corresponding part of the base on which the leaves of the pad are to rest.

In my present invention I provide a construction in which the pad-holding arches are mounted below the upper surface of the supporting base and are so mounted that they may be turned to a horizontal position without the necessity of long slots or slots projecting substantially beyond the axis of rotation of the arches.

In my invention I provide a base which may be a plate of any suitable material, either metallic or plastic material, or a fibrous material such as that commonly known as Masonite. Preferably the plate has the upper edge turned down to tilt the surface upwardly from its front edge, giving a desirable inclination to the surface of the base. On one half, for example the left half, of the base is provided a pair of narrow parallel slots substantially parallel to the lower edge of the base. Underneath the slots and clipped to the undersurface of the plate is a hinge element in which may be hinged the lower ends of one leg of each arch. The arches may be of any suitable form and are preferably formed of a single length of wire bent to form a pintle part in the hinge element, extensions from opposite ends of the pintle part horizontally for a short distance below the slots, then upwardly through the slots a height somewhat greater than the thickness of the calendar pads, then arching downwardly through locking holes in the opposite half of the base as, for example, in the right hand half.

When the ends of the wire arches are released

from the locking openings they may be tilted on the hinge element, the short horizontal extensions rising up through the slots and being of such length that when they are vertical the upright or vertical arm of the arch will lie horizontally flat against the surface of the base and the calendar pad may then be removed.

The various features of the invention are illustrated, by way of example, in the accompanying drawing in which

Fig. 1 is a plan view of a desk calendar embodying my invention;

Fig. 2 is a side view of the desk calendar;

Fig. 3 is an inverted plan of the calendar base;

Fig. 4 is a part vertical section on a somewhat larger scale taken on line 4—4 of Fig. 1;

Fig. 5 is a substantially horizontal section of a part of the base taken on line 5—5 of Fig. 2;

Fig. 6 is a detail perspective of a clip comprising the hinge element.

In the embodiment of the invention shown in the accompanying drawing, the base is formed of a plate 10 having an upwardly tilted flat part 11 extending upwardly from the lower edge 12 and then curved downwardly as at 13 to a rear edge 14. The downward edge thus forms a flange which tilts the rear edge of the base upwardly to give it an inclination desirable in the use of the calendar. By turning the plate downwardly as at 13 it is also possible to use materials for the plate which are not readily bent at a sharp angle as, for example, fibrous material such as Masonite. This construction also gives an attractive appearance. The flat part 11 of the base is somewhat wider than the calendar pad which is to be mounted on it, as shown in Fig. 1, so that part of the calendar pad will be on the right-hand half of the base and the other part on the left-hand half.

The calendar pad indicated at 15 is provided, as is usual, with a pair of openings 16 and 17 through which are threaded a pair of pad-holding elements or arches 18 and 19, one for each of the openings 16 and 17 respectively. These holding elements 18 and 19 are so mounted on the base 11 that they may be tilted counterclockwise, as indicated in Fig. 4, to enable the calendar pad 15 to be inserted, removed and replaced.

These holding elements 18 and 19 extend through suitable slots 20 and 21 in the left half of the base, when viewed in its usual position, or in the opposite half as shown in Figs. 3 and 5, and are hinged in a hinge element or clip 22 as shown in Figs. 2, 3, 4 and 6. This hinge element

or clip is preferably made of metal and comprises a flat part 23 resting on the upper surface of the pad between the slots 20 and 21 and with downturned portions extending through these slots and bending reversely into extensions 24 and 25 which thereby clamp the part of the base between these hinges and secure the clip in position.

Other parts 26 and 27 of the extension are separated from the parts 24 and 25 and spaced to receive and hold a horizontal mid portion 28 of a wire forming the holding elements or arches 18 and 19. The part 28 rotates between the parts 24 and 26 and 25 and 27 in the manner of a pintle or rock shaft. From the opposite ends of the pintle portion 28 the wires extend horizontally in short lengths 29 and 30 immediately beneath the slots 20 and 21 and then upwardly through the slots to form vertical extensions 31 and 32.

These extensions are arched at their upper ends and then extend vertically downwardly in lengths 33 which pass through locking openings 34 and 35 in the opposite half of the base. The parts of the downturned arms 33 that extend into the locking openings 34 and 35 are notched as at 36, Fig. 4, so that when pushed into the openings 34 and released they lock and hold the arches or holding elements in position.

When the arches are pressed together, that is, the vertical elements 33 pressed toward the vertical extension 31, the notched part is released and the arches may be tilted backwardly as shown in Fig. 4 until they lie horizontally against the base sufficiently to permit removal of the pad.

The above invention provides a desk calendar stand in which the holding elements may be very easily and freely tilted backwardly while at the same time the base underneath the calendar sheets is continuous and free from slots throughout the entire writing area thereof. The construction is also one which may be made of a wide variety of material such as compressed fibers, plastics, etc., as well as metal.

What I claim is:

1. A desk calendar pad which comprises a base plate, a pair of spaced elongated openings in said base at one side of a median line, the longer dimensions of said openings being parallel and in a direction at a right angle to said median line, a hinge element secured to said base plate above the upper surface and below the under surface of said base plate and a pair of spaced substantially parallel wire pad holders pivotally supported in said hinge element, one of said

holders extending horizontally below one of said elongated openings toward said median line then upwardly through one of said openings and above said plate and then bent downwardly over said median line and secured to said plate on the opposite side of said median line and the other of said holders extending horizontally below the other of said elongated openings toward said median line then upwardly through the other of said openings and above said plate and bent downwardly over said median line and secured to said plate on the opposite side of said median line whereby said pad holders may be released and tilted on said hinge element to swing the horizontal parts of said holders upwardly through their respective openings and to swing the upwardly extending parts downward to the upper surface of said plate.

2. A desk calendar pad which comprises a base plate, a pair of spaced elongated openings in said base at one side of a median line, the longer dimensions of said openings being parallel and in a direction at a right angle to said median line, a hinge element secured to said base plate above the upper surface and under the lower surface of said plate between said openings and toward the end of said openings farthest from said median line, said hinge element having parts extending through said openings to secure said hinge element to said plate and a pair of calendar pad holders comprising a single wire pivoted in said hinge element one pad holder extending on one side of said hinge element below one of said elongated openings toward said median line then upwardly through one of said openings and above said plate and bent downwardly over said median line and secured to the plate on the opposite side of said median line, the other pad holder extending on one side of said hinge element below the other of said elongated openings toward said median line then upwardly through the other of said openings and above said plate and bent downwardly over said median line and secured to said plate on the opposite side of said median line whereby the two parts of said wire on opposite sides of said hinge element may be tilted to swing the horizontally extending parts of said wires upwardly through their respective openings and to swing the upwardly extending parts downwardly to the upper surface of said plate.

3. The pad of claim 1 in which the free ends of said pad holders are notched and in which the base plate has openings to receive the ends of said holders and to engage said notches.

JOHN F. BANNON.
